UNITED STATES PATENT OFFICE.

EMIL P. STARY, OF CEDAR RAPIDS, IOWA.

FROST-PROOF BOX.

1,151,132.

Specification of Letters Patent. Patented Aug. 24, 1915.

Application filed July 14, 1913. Serial No. 778,978.

To all whom it may concern:

Be it known that I, EMIL P. STARY, a citizen of the United States, residing at Cedar Rapids, in the county of Linn and State of Iowa, have invented a new and useful Frost-Proof Box, of which the following is a specification.

This invention relates to a box or housing particularly designed to hold a water meter or the like, one of its objects being to provide means whereby air will be caused to circulate within the box from a point below the frost line upwardly to the top of the box, thus to keep the meter at a higher temperature than that of the surrounding frozen ground so that freezing of the meter in cold climates is prevented.

Another object is to provide improved means for maintaining the meter at a temperature above freezing without requiring the use of an anti-freezing mixture, packing or air forcing means.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings, Figure 1 is a vertical section through one form of box embodying the present improvements. Fig. 2 is a plan view thereof with the lid removed. Fig. 3 is a view similar to Fig. 1 and showing a modified form of box. Fig. 4 is a plan view thereof with the lid removed. Fig. 5 is another central vertical section showing a further modification. Fig. 6 is a plan view thereof with the lid removed.

Referring to the figures by characters of reference 1 designates a box of any desired material of such length as to extend below the frost line. This box is provided with any suitable cover 2 adapted to be flush with the surface of the ground.

The principal feature of the present invention resides in the provision of means whereby a circulation of air may be set up automatically so that the warm air at the lower end of the box can be caused to rise

within the box and thus keep warm the meter M supported in the upper portion of the box and connected to the water pipes P. This circulation is induced by the increased weight of the column or columns of air due to the presence at the top of the column or columns of a layer of relatively cold air. This cold air is produced by the exposure of the upper part of the body of air in the chamber to the relatively lower outside temperature. This cold layer will fall if its place be taken by air free to pass to the top of the chamber and of higher temperature, and so of less weight than the cold layer. One means of creating a circulation of air in an upward direction from the bottom of the box to the meter M consists of a by-pass 3 arranged outside of but integral with the box 1, this by-pass having an air inlet 4 at its upper end and an air outlet 5 at its lower end. It will be apparent that by utilizing a box such as shown in Figs. 1 and 2, the warm air contained within the bottom of the box and below the frost line will ascend within the box along the walls thereof while the cold air of greater density will descend at the center of the box as indicated by arrows, thus raising the temperature of the meter M and its contents. Obviously a circulation may be established in other ways as, for example, by arranging in the box 6, shown in Fig. 3, an inner casing 7 mounted on supports 8 so as thus to be held elevated above the bottom of the box 6. The warm air will ascend from the lower portion of the box through the by-pass 9 between the inner casing 7 and the box 6 and will displace the cold air in the top of the casing 7 and which will descend as indicated by arrows.

Instead of utilizing an inner concentric casing 7 as shown in Fig. 3, an interior by-pass 10 can be arranged within one or more corner portions or along one or more sides of the casing 11 as shown in Figs. 5 and 6. Where an inner by-pass 10 is employed, it is preferred to extend a deflector 12 under the lower end of the by-pass so that all of the warm air will not ascend through the by-pass. The circulation of air has been clearly indicated by arrows. Obviously in all of the structures described the boxes are to be of such length as to extend desired distances below the frost line, it being possible thus to keep the meter near the top of the box where it is kept at a raised temperature by

the cold air descending from the top of the box and which displaces the warm air which is located in the bottom portion of the box. In every instance, furthermore, the box is 5 closed at its top by a lid so as to prevent the escape of the ascending warm air. By utilizing a by-pass as in Fig. 1, although the column of air at the left wall is protected by the earth, the by-pass 5 is still more protected and the contained air is still warmer 10 so that the air will descend along the left wall and rise in the by-pass. This is likewise true of the structures shown in Figs. 3 and 5.

15 It will be apparent that by providing a structure such as herein described, it is unnecessary to utilize any packing, non-freezing compound, or the like, for the purpose of preventing freezing in the meter, and 20 furthermore, it is unnecessary to extend the water pipes through any heating medium or to provide any mechanical means for creating a circulation of a heating medium outside of the meter.

25 What is claimed is:—

1. The combination with a box adapted to be embedded in the ground and to extend below the frost line, of means for directing upwardly to the top of the box from the bottom thereof warm air displaced by a descending column of cold air.
2. A device of the class described including a box adapted to be embedded in the ground and to extend below the frost line,

a by-pass for directing warm air from the 35 bottom to the top of the box when displaced by a descending column of cold air, and a closure for the upper end of the box.

3. A box adapted to be embedded in the ground adjacent and below the frost line 40 and having separate passages extending from the upper to the lower portions thereof, and a closure for the upper end of the box, said passages constituting means for 45 effecting the upward displacement of warm air by the descent of cold air of greater density, thereby to raise the temperature in the upper portion of the box.

4. The combination with a box adapted to be embedded in the ground above and below the frost line, and a closure for the upper end of the box, of means supported within the box and spaced from the top and bottom thereof and from the wall of the box, whereby a central passage is produced within the box, said central passage being surrounded by an annular passage for the ascent of warm air displaced by cold air descending within the central passage.

55 In testimony that I claim the foregoing 60 as my own, I have hereto affixed my signature in the presence of witnesses.

EMIL P. STARY.
